Patented April 5, 1904.

UNITED STATES PATENT OFFICE.

WILLIAM C. ANDERSON, OF LANSING, MICHIGAN, ASSIGNOR TO AMERICAN CUT GLASS CO., OF DETROIT, MICHIGAN, A CORPORATION OF ILLINOIS.

DESIGN FOR A CUT-GLASS VESSEL.

SPECIFICATION forming part of Design No. 36,865, dated April 5, 1904.

Application filed February 23, 1904. Serial No. 194,962. Term of patent 7 years.

To all whom it may concern:

Be it known that I, WILLIAM C. ANDERSON, a citizen of the United States, residing at Lansing, in the county of Ingham and State of Michigan, have invented a certain new, original, and ornamental Design for a Cut-Glass Vessel, of which the following is a specification, reference being had therein to the accompanying drawing, in which the figure is a 10 perspective view of the inverted vessel.

What I claim as my invention is—
The ornamental design for a cut-glass vessel, as shown.

WILLIAM C. ANDERSON.
